DISPLAY DEVICE

James R. Connor, New York, N. Y.

Application March 5, 1940, Serial No. 322,389

14 Claims.

(Cl. 35—53)

This invention relates to display devices useful for indicating the appearance of a room as furnished with different arrangements of furnishings such as movable articles of furniture, window curtains, lamps, etc., and different fixed articles of adornment such as wall paper, painted wall coverings, and interior trim such as base boards and window casings.

It is an object of the invention to provide the representation of a room having one or more of the articles above mentioned in the form of two or more panels formed of thin sheet material and upon which may be positioned patterns or models of the articles of furniture or other room furnishings, thus permitting the user to obtain a correct impression of the appearance of one or more walls and the floor of the room as thus furnished.

It is a further object of the invention to provide such a room representation in which the panels representing the floor and walls of a room are formed from a single sheet of thin flat material which is scored to provide crease lines about which the individual panels may be folded to overlie each other, thus rendering the display device very compact.

A still further object of the invention is to provide a mask having a plurality of openings therein which are generally shaped to represent the plan view of certain articles of furniture and which overlie pieces or samples of various covering materials which are used as finishing materials to cover such articles of furniture on the above described panels. Several such masks of similar formation, but differently colored or tinted to represent rugs or carpets of different colors or tints, are preferably provided so that the color effect of different rugs with selected colors of furniture covering materials may be easily observed and compared. If desired, the mask or masks may be made of portions of the actual rug, carpet, linoleum or other floor covering material.

Another object of the invention is to provide means in the form of one or more transparent masks which are made to scale and which are marked to indicate the intensity of illumination at one foot intervals from a standard electric lamp and by means of which the proper degree of illumination at various locations within the room may be determined for different uses, and also the number and spacing of the lamps required to secure the desired illumination may be easily determined. This application is a continuation in part of application Serial No. 234,392, filed on October 11, 1938, in my name.

Other and further objects of the invention will become apparent as the description thereof proceeds. For a better understanding of the invention, however, reference is made to the accompanying drawings in which:

Fig. 1 is a plan view of a display device embodying the invention with portions of the panels broken off;

Fig. 2 is a plan view on a reduced scale of the main supporting member of the display device of Fig. 1;

Figs. 3 and 4 are plan views of patterns or models adapted for use with the display device;

Fig. 5 is a plan view of the mask portion of the display device shown in Fig. 1;

Fig. 6 is a plan view showing a portion of the display device of Fig. 1 with an illumination indicating mask embodying the invention superposed thereon; and

Figs. 7 and 8 are modified forms of illumination indicating masks embodying the invention and adapted for use with the display device shown in Fig. 6.

Referring to Figs. 1 and 2, the main body or supporting member of the display device comprises a sheet S of thin, flat material such as heavy paper or cardboard, and which is scored to provide crease or fold lines 10, 11, 12 and 13, the rectangular panel 14 within these lines representing in general outline the floor of a room and the four surrounding rectangular panels 15, 16, 17 and 18 representing the four walls of the room, most of wall panel 17 being shown in Fig. 1, but the remaining panels 15, 16 and 18 being shown broken off near the floor panel 14. Adapted to cover substantially the entire panel 14, I provide a rectangular mask 19 which may be formed of cardboard or similar thin, light sheet material which may be colored as desired to represent

textile material such as rug or carpet material, or may be a textural material such as the actual carpet, rug, linoleum or other floor covering whose appearance in association with the other room furnishings it is desired to observe. The mask 19 (see Fig. 5) is provided with a plurality of openings 20, 21, 22, 23, 24, 25, 26, 27, 28, 29 and 30 which may be arranged as shown or in any other desired manner. A border line 31 may also be inscribed on the mask 19, if desired, preferably spaced from and parallel with its outer edges, as shown, the border line 31 being broken as shown in Fig. 1 to provide an offset portion 32 representing a door of the room. The opening 20 has the general shape of the top outline of a couch, the other openings, 21 to 30 in the

mask, representing chairs. Between the mask 19 and panel 14 I provide pieces of textile or other covering material, the piece 33 extending beneath the openings 27, 28, 29 and 30, piece 34 extending beneath opening 20, pieces 35 and 35a beneath openings 21 and 22 respectively, piece 36 beneath opening 23, piece 37 beneath openings 24 and 25 and piece 38 beneath opening 26. The pieces or samples of covering material 33, 34, 35, 36, 37 and 38 preferably extend considerably beyond the openings they underlie and may overlap each other, if desired, as shown in dotted lines in Fig. 1. This arrangement permits each material sample to be of generous size rather than of small dimensions so that its color, texture and pattern may be observed by the user of the device either by lifting the mask 19 or by withdrawing the desired sample from under the mask.

In further pursuance of the invention, pieces or panels of thin material such as colored cardboard or wood are provided to represent the outlines of other furniture furnishings which are usually made of wood, these panels being positioned as desired on the top of mask 19. Referring to Fig. 1, such a panel 39 is shown as representing a desk, panel 40 as representing a table, panel 41 as representing a bookcase, and panel 42 as representing a bridge table. Such panels may be shaped as desired and made of different sizes and colors as indicated in Fig. 1, and positioned as desired on the mask 19 in order to observe the effect of different furniture arrangements and different combinations of color in the room. If desired, small cut-outs or panels of cardboard or other material may be positioned in desired locations to represent electric lights, such a cut-out being shown at 43 as representing a side or wall lamp and the disc 44 as representing a table lamp (Fig. 1).

To observe the decorative effects of different treatments of the side wall or walls of the room the panel 17 is shown as being partially covered with a generally rectangular sheet 45 of textile material which may be colored or have a suitable design woven or printed therein suitable for window curtain or draping material. Over the sheet 45 is positioned a mask 46 shown more clearly in Fig. 4 as being provided with a pair of spaced apart window openings 47, 48 which may be generally rectangular, as shown, or of other desired shape. Mask 46 may be made of cardboard suitably covered with a solid coating of any desired solid color to represent a painted wall, or may be made of commercial wall paper either plain or figured with an appropriate pattern or design. Or it may be made of any other known wall covering material, for example, textile material or wood. By means of the arrangement described, the appearance of the side of the room with different selections of window draping material and wall covering material may be easily observed and compared by providing a plurality of sheets 45 and masks 46 made of different materials and in different colors.

In further pursuance of the invention, the appearance of the side of the room as affected by window casing and base boards made of different woods such as chestnut, maple, walnut etc., may be observed by providing one or a plurality of patterns 49, Fig. 3. These patterns may be made of cardboard, paper or other suitable material whose surface is treated with any known covering material such as paint, stain, lacquer, etc., to represent the color and grain of different woods,

As shown in Figs. 1 and 3, each pattern 49 comprises a base portion 50 which represents the base board, and two upstanding rectangular portions 51 and 52 provided with the respective window openings 53 and 54 which are spaced similarly to the window openings 47, 48 in mask 46. This arrangement provides narrow borders 55 and 56 which extend about the window openings 47, 48 and simulate window casings. If desired, the borders 55 and 56 may extend slightly within or past the edges 57, 58 of the window openings 47 and 48 so as to conceal these edges, as shown in Fig. 1. While the decorative features just described are shown in Fig. 1 only in connection with panel 17, it is to be understood that similar components of the same or different color arrangements may be provided for use with any one or all of the panels 15, 16 and 18 to represent one or more of the other walls of the room.

By forming the several component parts of the display device of thin, light material such as cardboard or paper and textile material, they may all be laid flat on top of main panel 14 and panels 15, 16, 17 and 18 then folded over so as to cover and contain them. A display device of the type described is readily portable and is adapted to the display of the wares of interior decorators, wall covering manufacturers, paint manufacturers, furniture manufacturers, window curtain manufacturers, floor covering manufacturers, architects and all others who supply, design or manufacture room furnishings or fixtures such as lamps etc.

Referring to Fig. 6, as a further feature of the invention, I provide a rectangular shaped panel 59 formed of any suitable transparent material as, for example, thin plastic sheet material, whose surface is inscribed or etched with a plurality of spaced circles C having a common center point 0. The panel also has inscribed on it, a set of semi-circular arcs C' arranged about a center 0' which lies substantially on the lower edge 60 of the panel. The circles C and semi-circles C' are spaced apart a distance representing 1 foot on the scale to which the display device is made. Each circle or semi-circle is marked, in the manner indicated in Fig. 7, with numbers indicating the intensity of illumination in foot-candles (F. C.) and also with the indicia "Fine Work," "Reading," etc., to indicate the character of work suitable to be performed in the several zones. These graduations and indicia are based on the use of a standard 100 watt tungsten filament bulb as the light source, it being understood that if a larger or smaller light source is used, the numbers and indicia indicating the degree of luminosity in the different zones will be made to correspond.

Fig. 6 also shows a plurality of cardboard discs 61, 62, 63, 64, 65 and 66 representing floor lamps and the cardboard panels 67 and 68 representing wall lamps. In using the panel 59 in connection with a lamp disposed on or close to the side wall of the represented room, the edge 60 thereof is disposed parallel to the edge of the mask 19 and with the center mark 0' disposed above the center of the disc or panel representing the light source, the panel shown being arranged to indicate the illumination about the lamp indicated at 64 in Fig. 6. With the illumination indicating panel in position, the intensity of the illumination at each point of the mask 19 disposed within the circles C or semi-circles C' may easily be read off. For a lamp which is disposed at a substantial distance from the represented wall of the

room as, for example, the lamp represented at 65, the center point 0 of panel 59 is disposed above the center of the disc 65 and the intensity of illumination in the several zones about the lamp may then be readily read off the graduations of the circles C. When the display device is arranged with the panels 15 to 18 lying flat, the circles C may be used to determine the illumination about a lamp disposed anywhere on the mask 19, the edge portion of the panel 53 projecting over and overlying one or more of the flat panels 15 to 18. In case the panels 15 to 18 are vertically disposed to represent the walls of the room, however, the semi-circular graduations C' must be used in connection with the determination of the illumination about a lamp disposed on or closely adjacent to a side wall of the represented room. This panel may be cut in two on the horizontal line indicated at 59a so as to provide two separate units, the upper one having the circular graduations and the lower one the semi-circular graduations.

A panel of the latter type is shown in Fig. 7 in which the panel 59' is similar to the lower portion of the panel 59 of Fig. 6 and includes the graduated semi-circles C' and their appropriate indicia, as shown, the circular zones being omitted. The use of this form of panel will be apparent from the above description of the use of the lower portion of panel 59.

In any case where the lamp is disposed closely adjacent to a corner of the room as, for example, the lamp represented by the disc 63 of Fig. 6, I provide a panel of the form shown in Fig. 8. In this form of the invention the panel 59' is square and the center point 0'' of the circular arcs C'' is disposed substantially at one corner of the panel. It is thus possible to position the center 0'' of the graduated arcs above the disc 63 when the side panels 15 and 16 are in vertically disposed position to represent the side walls of the room. The intensity of illumination at all points of the mask 19 disposed under the several zones defined by the substantially 90 degree circular arcs C'', may then be readily determined from the graduations.

By means of the invention it is readily possible to determine the proper position a lamp should have in order to give a desired degree of illumination at any portion of the floor area of a room. It is also readily possible to determine the number of lamps required in a room in order to provide a sufficient degree of illumination at the different portions thereof.

I have described what I believe to be the best embodiments of my invention. I do not wish, however, to be confined to the embodiments shown, but what I desire to cover by Letters Patent is set forth in the appended claims.

I claim:

1. A display device for guidance in the selection of materials for decorating a room and furniture comprising components formed of sheet material constituting a folder having at least two panels, one panel being a floor-representing panel and the other being a wall-representing panel, one or more samples of furniture-covering material disposed at spaced-apart positions on the floor panel, a mask simulating floor covering material or actually of floor covering material disposed over said samples and thereby concealing portions of said samples, said mask having furniture-shaped openings displaying furniture-shaped portions of said samples therethrough,

and a sample of material disposed on the wall panel.

2. A device of the class described comprising the elements combined and cooperating as set forth in claim 1 and further characterized by having said samples and mask unattached to and removable from the panels.

3. A display device for guidance in the selection of decorating materials for a room and furniture comprising components formed of sheet material and having at least two panels, one panel being a floor-representing panel and the other a wall-representing panel; one or more samples of furniture-covering material disposed at spaced-apart positions on the floor panel, a mask simulating floor covering material or actually of floor covering material disposed over said samples and having furniture-shaped openings displaying said samples throughout the extent of such openings, said mask concealing the remainder of such samples, a sample of window or door draping material disposed on the wall panel, and a piece of wall covering material disposed over the last named sample and having at least one window or door simulating opening therein to display portions of said draping material therethrough.

4. A display device of the class described comprising a substantially flat component having an outline representing a floor plan, one or more samples of material adapted for the covering of furniture disposed at spaced apart positions on said components, a mask simulating a rug or actually a rug or floor covering and having a plurality of openings therein disposed over the samples respectively, each opening representing in shape the outline of an article of furniture and a plurality of substantially flat components disposed on said mask between the openings 40 therein, each of said last-named components representing in shape an article of furniture.

5. A display device comprising a component formed of thin sheet material creased to provide four fold lines arranged to divide the component into a floor-representing panel and four wall-representing panels, one or more samples of furniture-covering material disposed at spaced apart positions on the floor representing panel, means disposed over said samples arranged to conceal 50 a portion only of each sample and simulating floor covering material, said means having furniture-shaped openings displaying said samples throughout the extent of said openings, and means simulating wall and window decorative materials disposed on one or more of the wall representing panels.

6. A display device comprising at least two panels formed of sheet material, one being a floor-representing panel and the other a wall-representing panel, one or more samples of furniture-covering material disposed at spaced apart positions on the floor panel, a mask for concealing portions of said samples and having furniture-shaped openings displaying correspondingly shaped portions of said samples therethrough, said mask simulating carpet material, panels representing articles of wood furniture in plan view disposed at spaced apart positions on said mask, a sample of wall covering disposed on the wall panel and one or more panels representing articles of wood furniture in elevation disposed at spaced apart points on said wall covering.

7. A display device comprising components formed of sheet material and having at least two panels, one of said panels being a floor-repre-

senting panel and the other being a wall-representing panel, one or more samples of furniture-covering material disposed at spaced apart positions on the floor panel, means for concealing portions only of said samples and displaying furniture-shaped portions thereof, a sample of wall covering material disposed on the wall panel and having at least one window opening therein, a piece of window draping material disposed behind said window opening and a panel disposed in front of said wall covering material and having a narrow border formed of material colored to simulate window casing trim disposed around said window opening.

8. A display device adapted for representing the appearance of articles of furniture in a room and comprising, in combination, a component formed of flat sheet material, one or more samples of textile material adapted for covering furniture disposed at spaced apart positions on but unattached to said component and a mask colored to simulate floor covering material or actually of floor covering material disposed over said samples, said mask being provided with an opening over each sample which is smaller than the sample and which has the shape of an article of furniture.

9. A display device adapted for representing the appearance of a wall of a room comprising, in combination, a panel formed of thin sheet material, a sample of wall covering material disposed on said panel and having at least one window opening therein, a sample of window draping material disposed behind said window opening and extending beyond the margin of the window opening and a narrow border formed of thin sheet material colored to simulate window-casing trim disposed above the wall covering

material around the margin of the window opening.

10. A display device comprising, in combination, a floor panel representing the floor of a room on a reduced scale, one or more movable markers representing one or more light sources disposed on said floor panel and a panel formed of transparent sheet material for indicating the intensity of the light from the light source represented by a movable marker, said transparent panel being inscribed with a reference point adapted to be disposed above a marker and also with a series of luminous intensity indications arranged around the reference point, said indications being disposed in the manner to correspond to the above-mentioned reduced scale.

11. A display device as set forth in claim 10 in which the luminous intensity indications comprise a plurality of circles having the inscribed reference point as a common center.

12. A display device as set forth in claim 10 in which the reference point is inscribed on the panel near one edge thereof and the luminous intensity indications comprise a series of semi-circles having the reference point as a common center.

13. A display device as set forth in claim 10 in which the reference point is inscribed on the panel near one corner thereof and the luminous intensity indications comprise a series of circular arcs extending over substantially 90 degrees and having the reference point as a common center.

14. A display device as set forth in claim 10 in which the luminous intensity graduations comprise a series of concentric circular arcs spaced apart a distance corresponding to one foot on the reduced scale of the floor panel.

JAMES R. CONNOR.
